US00D666501S

(12) **United States Design Patent**
Brummelhuis et al.

(10) **Patent No.:** **US D666,501 S**
(45) **Date of Patent:** **** Sep. 4, 2012**

(54) **BOTTLE WITH PUMP**

(75) Inventors: **Bas Jeroen ten Brummelhuis**, Shanghai (CN); **Andrew Peter Sharpe**, Wirral (GB)

(73) Assignee: **Conopco, Inc.**, Englewood Cliffs, NJ (US)

(**) Term: **14 Years**

(21) Appl. No.: **29/397,530**

(22) Filed: **Jul. 18, 2011**

(30) **Foreign Application Priority Data**

Jan. 28, 2011 (EM) 001812512-0001

(51) **LOC (9) Cl.** **09-01**

(52) **U.S. Cl.** **D9/694**

(58) **Field of Classification Search** D9/682-694, D9/516-575, 434-454; 215/379-385; 220/669-675; 222/129, 135, 153.01, 153.03, 222/153.04, 153.09, 153.11-153.14, 182, 222/631, 635, 209, 211-213, 215, 321.7-321.9, 222/372, 373, 378, 379, 383.1, 384-386, 222/398, 400.7, 400.8, 401, 402.1-402.25
